COMBINATION BOTTLE OPENER AND NUT CRACKER

William E. Frawley, Jr., and John R. Frawley,
Birmingham, Ala.

Application October 2, 1947, Serial No. 141,710

Term of patent 3½ years

(Cl. D44—1)

To all whom it may concern:

Be it known that we, William E. Frawley, Jr., and John R. Frawley, residing at Birmingham, county of Jefferson, State of Alabama, have invented a new, original, and ornamental Design for Combination Bottle Opener and Nut Cracker, of which the following is a specification, reference being had to the accompanying drawing, forming a part thereof.

Fig. 1 is a side elevational view of a combination bottle opener and nut cracker showing our new design;

Fig. 2 is a view similar to Fig. 1 and showing the jaws open to illustrate the configuration of the handle for the upper jaw;

Fig. 3 is a top plan view;

Fig. 4 is a bottom plan view; and,

Fig. 5 is a front view with the jaws closed as in Fig. 1.

We claim:

The ornamental design for a combination bottle opener and nut cracker, as shown and described.

WILLIAM E. FRAWLEY, JR.
JOHN R. FRAWLEY.
